UNITED STATES PATENT OFFICE.

BURR B. BLOOD, OF CHICAGO, ILLINOIS, ASSIGNOR, BY MESNE ASSIGNMENTS, TO JEWEL PHONOPARTS COMPANY, OF CHICAGO, ILLINOIS, A CORPORATION OF ILLINOIS.

PHONOGRAPH REPRODUCER.

1,419,913.

Specification of Letters Patent. Patented June 20, 1922.

Application filed January 16, 1919. Serial No. 271,377.

To all whom it may concern:

Be it known that I, BURR B. BLOOD, a citizen of the United States, and a resident of Chicago, in the county of Cook and State of Illinois, have invented a certain new and useful Improvement in Phonograph Reproducers, of which the following is a description, reference being had to the accompanying drawing, which forms a part of my

specification.

My invention relates to sound reproducers for phonographs and has for its object the provision of a construction wherein the stylus-bar is provided with a cross-head so formed that a proper pivotal mounting of the stylus-bar on the shell or casing may be provided which enables all vibrations encountered by the stylus or needle to be thoroughly imparted to the flexible or mica diaphragm of the reproducer without, however, permitting undue or improper vibration of the stylus-bar; the construction enabling a reproduction of sounds in greater volume and without loss in the tone quality.

The object of my invention as well as its advantages will be more fully comprehended from the following detailed description of the drawing, wherein:—

Figure 1 is a front elevation of my improved reproducer with a portion of the tone arm to which it is secured.

Figure 2 is a side elevation of the reproducer, looking at the stylus receiving socket of the stylus-bar.

Figure 3 is a detail perspective view of the cross-head of my improved stylus-bar.

In the exemplification of my invention, the casing or shell 10 is provided with the usual inwardly disposed flange 11 whereby the usual gaskets or yielding rings and the flexible or mica diaphragm are held in place in the casing; the diaphragm being also held in place by the back 12 with a gasket or rubber ring intervening, at the marginal edge of the

diaphragm.

The back is provided with a central outlet or opening provided with a tone-arm connection or elbow as at 13 which is preferably removably secured to the back; while the back itself is removably secured to the shell or casing.

The periphery of the shell or casing 10 is provided with the usual lugs 14, 14, spaced apart so as to receive therebetween the cross-head 15 of the stylus-bar 16. The cross-head

15 is shown provided with a socketed extension or stem 17, which is disposed at the longitudinal axis of the stylus-bar, in order that the stylus or needle 18, which is removably held in the socket of the extension 17 by set-screw 19, may be coincident with the longitudinal axis of the stylus-bar as shown in Figure 1.

The lugs 14, 14 are spaced apart, or in other words, the cross-head 15 of the stylus-bar is of such length that the cross-head may be placed between the lugs 14, 14 without contacting therewith; and in the preferred form, the length of the lugs 14, 14, or rather the width of the cross-head 15, is such, relative to the distance from the ends of the lugs 14 to the perimeter of the casing or shell, that slight "play" or space will be provided intermediate of the side of the cross-head and the perimeter of the casing when the stylus-bar is in proper or operative position. The ends of the cross-head 15 are both provided with flared or bevelled sockets as at 20 in Figure 3; the sockets being preferably located coincident with the longitudinal axis 75 of the cross-head 15 and adapted to receive the pivot forming members or pointed screws 21, 21, which extend through the lugs 14, 14, and have threaded relation therewith.

The flared sockets 20 are of such size as 85 to permit the ends of pivot-forming members 21 to enter the sockets and merely contact with the cross-head 15 at the points of members 21 so as to provide a sensitive pivot or support for the stylus-bar.

In my improved construction, the cross-head of the stylus-bar is provided merely with the two bearing or pivotal points on the shell or casing and thus readily allow all of the stylus vibrations to be freely 95 transmitted through the stylus-bar to the center of the flexible or mica diaphragm.

In order, however, to prevent improper play, and, therefore, undesirable vibrations between the cross-head of the stylus-bar and 100 the pivot-forming members, it is essential that the pivot-forming members be brought into firm holding relation with the cross-head so as to prevent any movement of the latter in a direction lengthwise thereof.

At the same time, it has been found in practice that in adjusting the pivots for the stylus-bar so as to prevent lateral or side-wise movement thereof, the pivot-forming members are brought into such firm or bind- 105

ing relation with the cross-head that the tone quality of the reproducer is seriously affected. In order, therefore, that a too rigid or stiff connection between the pivot forming members and cross-head of the stylus-bar may not be possible, I provide, in the particular exemplification, a slot 22 disposed transversely of the cross-head 15, extending from one of the longitudinal sides thereof to a point somewhat beyond the longitudinal axis of the cross-head, or rather to a point beyond the plane in which the pivot-forming members 21 are disposed. The slot 22 extends entirely through the cross-head from front to rear thereof and terminates at a point slightly removed from one of the longitudinal sides of the cross-head so as to leave sufficient metal to firmly hold the partially dismembered portion or end of the cross-head in place.

It is evident from the construction shown and described that the slot 22 will permit the end of the cross-head, intermediate of the slot and the adjacent pivot-forming member, to yield sufficiently, when the members 21, 21 are screwed into firm contact therewith, so as to prevent a binding or non-yielding relation between the pivot-forming members 21, 21, and the cross-head of the stylus-bar.

With my improved construction, a more delicate adjustment of the pivot points may be obtained, as a result of the flexible or springy nature of the partially dismembered portion or end of the cross-head, thereby providing a yielding relation with the pivot forming members.

At the same time the yielding relation be-

tween the cross-head and pivot forming members is such that no undue vibration or "chatter" is possible; while at the same time the delicate vibrations encountered by the stylus or needle will be properly transmitted through the stylus-bar to the flexible or mica diaphragm of the reproducer.

The slot 22 is, of course, formed near the end of the cross-head as shown and preferably at what may be called the lower end of the cross-head when the reproducer is in the position shown in Figure 1; although a similar slot might be formed at the other end of the cross-head; and certain modifications in the general construction may be made without, however, departing from the spirit of my invention.

I have found in practice, that with my improved construction, the volume of the tones is not only greatly increased, but that clearer tones are obtained and the finer details or undertones are reproduced because of the yielding adjustment obtainable.

What I claim is:—

In a phonograph reproducer, a stylus-bar provided with a cross-head and stylus-holding portion at one end, the cross-head adjacent one of its ends being provided with a slot extending transversely therethrough from one longitudinal side to a point beyond the longitudinal axis of the cross-head so as to provide a partially severed end portion adapted to yield in a direction lengthwise of the cross-head.

BURR B. BLOOD.
